(57) **CLAIM**

The ornamental design for a capsule holder cabinet, as shown and described.

DESCRIPTION

FIG. 1 is a Front perspective of a capsule holder cabinet showing my new design;

FIG. 2 is a Front view thereof;

FIG. 3 is a Back view thereof;

FIG. 4 is a Left Side view thereof;

FIG. 5 is a Right Side view thereof;

FIG. 6 is a Bottom view thereof;

FIG. 7 is a Top view thereof.

FIG. 8 is a Front view shown in the open position thereof; and, FIG. 9 is a Front view showing environment thereof.

The broken lines shown in FIGS. 8 and 9 of the capsule holder cabinet, which are immediately adjacent to claimed surfaces, are directed to the environment and are for illustrative purposes only; the broken lines form no part of the claimed design.
